United States Patent Office

Des. 213,287
Patented Feb. 4, 1969

213,287

BASEBALL GLOVE OR SIMILAR ARTICLE

Joseph N. Khazzam, Baldwin, N.Y., assignor to Regent Sports Co., New York, N.Y., a partnership

Filed Aug. 9, 1967, Ser. No. 8,179

Term of patent 14 years

U.S. Cl. D2—361

Int. Cl. D2—07

The essential features of my design reside in the full line disclosure.

I claim:

The ornamental design for a baseball glove or similar article, as shown and described.
